UNITED STATES PATENT OFFICE.

VICTOR G. MORGAN, OF LOS ANGELES, CALIFORNIA, ASSIGNOR, BY DIRECT AND MESNE ASSIGNMENTS, TO PARK W. COWAN, OF LOS ANGELES, CALIFORNIA.

ADJUSTING MEANS FOR PRINTING-PRESS ROLLERS.

1,240,078.

Specification of Letters Patent. Patented Sept. 11, 1917.

Application filed April 19, 1915, Serial No. 22,261. Renewed February 6, 1917. Serial No. 146,987.

To all whom it may concern:

Be it known that I, VICTOR G. MORGAN, a citizen of the United States, residing at Los Angeles, in the county of Los Angeles 5 and State of California, have invented new and useful Improvements in Adjusting Means for Printing-Press Rollers, of which the following is a specification.

This invention relates to trucks for inking rollers, and especially pertains to means 10 for adjusting the size of inking roller trucks.

Inking rollers are generally constructed having an inking surface formed of gelatinous material.

15 In the manufacture of inking rollers of the character above described, it has been found that the diameter of the rollers varies slightly and that different weather conditions also cause variations in the diameter.

20 Trucks now in general use for inking rollers are of metal and of substantially the same diameter for any given size of roller. It has been found in practice that if the roller is less in diameter than the trucks, the type 25 are not sufficiently inked, and if the roller is larger in diameter than the trucks, slurring and filling of the type results and in time the roller surface is cut.

I obviate these objections by providing 30 trucks which can be adjusted as to their diameter, and providing means whereby a fine adjustment may be made. The trucks constructed according to my invention are in general of the usual size and appearance 35 and may be adjusted by an ordinary wrench which is applied to a nut forming a part of the truck.

I attain these objects by the truck illustrated in the accompanying drawing, in 40 which:

Figure 1 is an elevation of an inking roller broken on the dot and dash lines, with my improved truck applied thereto, one truck being shown in vertical section.

45 Fig. 2 is a perspective view of a truck.

More specifically, 3 indicates a metallic cylindrical core which carries a coating 4 of gelatinous material. Stub shafts 5 and 6 are secured to the ends of the roller, preferably integral therewith, and carry thereon 50 adjustable trucks 7 and 8 which ride upon tracks 9 and 10 mounted on the press bed 21. The roller rides over the form 11. Saddles 12 and 13 are provided which move the inking 55 roller and are secured to the operating

mechanism of the press. An ink disk or inking cylinders, not shown, may be used to apply the ink to the rollers.

The trucks 7 and 8 are keyed to the stub shafts 5 and 6 respectively, as indicated at 60 14, so that the roller will rotate in its travel. Each truck comprises a sleeve 15 threaded at one end and carrying at the other end a collar 16 which is preferably integral with the sleeve. Collar 16 has a face 17 which 65 converges from the center toward the edges, forming a wedge surface. A ring 18 of some expandable material which is in the form of a washer and acts as a tire, is set onto the sleeve 15. The ring 18 is preferably made of rubber and has its lateral faces inclined from the center toward the edges to form in cross section a wedge shape. A collar 19 is loosely mounted on the shaft for longitudinal sliding movement and has a 70 face which converges from the center outward, forming a wedge surface to coöperate with the surface on the washer. Engaging collar 19 is a thin nut 20 the threads of which engage threads on the sleeve 15. Nut 75 20 is preferably hexagonal in form to form a hold for a wrench.

To increase the diameter of the truck, a wrench is applied to nut 20 and the nut is screwed so that it will force collar 19 toward 80 collar 16, thereby compressing the tire member 18 and expanding it to produce a greater diameter. To decrease the diameter of the truck, the nut 20 is screwed so that it moves away from collar 19 and the tire member 85 18 due to its own resiliency decreases in diameter, expanding longitudinally. It is obvious that for a given roller the truck may be adjusted in diameter so that the inking roller will bear upon the type with the desired pressure, thereby protecting the 90 roller and assisting in the quality of the work.

What I claim is:--

1. In an inking roller for printing presses, a truck comprising a threaded sleeve, a collar secured thereto, a collar slidably mounted on said sleeve, an expandable tire or ring form filling the space between said collars and of solid elastic material mounted on 100 said sleeve between said collars, and a nut engaging with the threads on said sleeve and in engagement with said sliding collar to expand the tire.

2. In an inking roller for printing presses, 105

a truck comprising a threaded sleeve, a collar having a wedge face secured thereto, a collar having a wedge face slidably mounted on said sleeve, an expansible tire of ring ⁵ form filling the space between said collars and of solid elastic material mounted on said sleeve between said collars, and a nut

engaging with the threads on said sleeve and in engagement with said sliding collar to expand the tire.

10

In witness that I claim the foregoing I have hereunto subscribed my name this 3rd day of March, 1915.

VICTOR G. MORGAN.
